JOHN P. HUMPHREY
by Atty. N. D. DuBois.

UNITED STATES PATENT OFFICE.

JOHN P. HUMPHREY, OF SPRINGFIELD, ILLINOIS.

SUNSHADE FOR VEHICLES.

1,393,130.

Specification of Letters Patent.

Patented Oct. 11, 1921.

Application filed December 24, 1920. Serial No. 432,964.

To all whom it may concern:

Be it known that I, JOHN P. HUMPHREY, a citizen of the United States, residing at Springfield, in the county of Sangamon and State of Illinois, have invented a new and useful Sunshade for Vehicles, of which the following is a specification.

The invention relates to sun shades such as are used on automobiles and other vehicles 10 to protect the eyes of the driver from the glare of sunlight and from dust and smoke carried by the wind.

The purposes of the invention are: to provide a sun shade adapted for use in connection with the wind-shield-standards of any one of a number of vehicles of different makes; to provide improved means for connecting the sun shade with the wind-shield-standards of any common manufacture; and 20 to provide improved details of construction adding to the convenience and effectiveness of the sun shade.

The invention is illustrated in the annexed drawing, to which reference is hereby 25 made, and will now be fully described and the novel features thereof will be recited in the claim.

Figure 1 is an elevation of a sunshade embodying my invention, attached to the wind-shield-standards of a vehicle; Fig. 2 is a 30 side elevation of one of the brackets supporting the sun shade; Fig. 3 is an edge view of the right hand bracket, shown in Fig. 2, and shows in dotted lines the opposite or reverse bending of the blank to form a left-hand bracket; Fig. 4 is a plan of the blank from which the brackets are formed; Fig. 5 is a plan view, on a reduced scale, of the skeleton frame of the sun shade; and Fig. 6 35 is a reduced plan view of the envelop apart from the skeleton frame.

The same reference numerals designate the same parts in all the views.

The protective member or vizor of the sun shade, designated as a whole by the numeral 10; comprises a skeleton frame designated as a whole by the numeral 12; bolt-ends 13 permanently attached to the skeleton frame; and an envelop 14 of waterproof fabric completely inclosing the skeleton frame. The skeleton frame is preferably formed from a single rod bent as will now be described.

To form the skeleton frame 12 from a single rod as indicated in Fig. 5 the procedure will be as follows: starting with one end of

the rod at the point 15, run straight to 16; at the point 16 bend the rod at right angles to itself and run straight to 17; at the point 17 bend the rod at right angles to itself and run straight to 18; at the point 18 bend the rod at right angles to itself and run straight to 19; at the point 19 bend the rod at right angles to itself and run straight to 20; at the point 20 bend the rod at right angles to itself and run straight to the point 21. At the points 15 and 21 the terminals of the rod will be brazed to the body of the rod as shown at 22. The bolt-ends 13 will be securely connected with the frame 12 by brazing or hard solder 23. The bolt ends are of such length that they may be readily adapted to wind-shield-standards 30 at various distances apart from each other.

The envelop 14 (Fig. 6) preferably consists of a single piece of waterproof fabric folded longitudinally, wrong side out, along its central line 24 and sewed as indicated by the dotted line 25 along one end and one side. At the sewed end of the envelop is a 75 part left unsewed to permit spreading apart the members of the envelop to form an opening 26 through which one bolt-end may be inserted. After being sewed as described, the envelop will be turned right side out and the skeleton frame 12 will be inserted in the envelop with one bolt-end 13 extended outwardly through the opening 26; the free ends of the parallel members of the envelop will then be turned in and stitched together, 80 and a line of stitches 9 (Fig. 1) will be made around the inside of the skeleton frame, to 85 securely connect the envelop with the frame. Here it is to be noted that the skeleton frame is a smooth structure which may easily be slid into the envelop; and when the line of 90 stitching 9 is completed the members of the envelop will lie flat against each other; both sides of the shield will be alike; the stitching will give an attractive finish to the shield, and the shield, as a whole, will combine 95 lightness and strength.

The brackets for supporting the sun shade are formed from blanks pressed from sheet metal, one of which is shown in Fig. 4. Each blank comprises a body 27; lateral extensions 28; ears 29 having holes 30 to receive bolts for connecting the brackets with

the standards, and an inclined longitudinal member 31 having an eye 32 to receive the bolt ends 13.

A wind-shield 38, of a type commonly used on vehicles, oscillates in bearings near the upper ends of fixed vertical standards 36. The wind-shield usually has two lateral shafts 37, one at each end of the wind-shield; and is equipped with washers 32 and nuts 10 33 as shown. In practice, when the wind-shield is properly adjusted, the nuts on the shaft 37 will be tightened to hold the wind-shield in any inclined position in which it may be placed.

15 The sun shade herein shown and described being designed for use in conjunction with various wind-shields, it is important that the brackets 34 and 35, used to support the sun shade on the standards 36, shall not interfere with the movement of the wind-shield 38, or the manipulation of the nuts 33, which secure the wind-shield in different inclined positions. I therefore provide brackets 34 and 35 inclined rearwardly to 20 permit desired partial rotation of the wind-shield, and inclined laterally to permit free manipulation of the nuts 33. The brackets 34 and 35 are in pairs, one being right-hand and the other left-hand, but in either case 25 the brackets will be formed from exactly similar blanks 27, the only difference being that the members of the blank will be bent as shown by full lines in Fig. 3 to form a right-hand bracket; and will be bent as 30 shown by dotted lines in the same view, to form a left-hand bracket.

To form the left-hand bracket shown in detail in Figs. 1 and 2: Beginning with the blank in the flat position shown in Fig. 4, 40 the member 28 will be bent downwardly along the respective dotted lines 39, 39 until they occupy positions at right angles to the face of the body 27; the member 31 will be bent upwardly along the line 7, 7, to form 45 the intermediate member 40 outwardly inclined relatively to the face of the body 27; and will be bent along the line 8, 8, to form the eye-member 41 occupying a plane spaced apart from but parallel to the plane of the 50 body 27.

The bolt ends 13 extend through the eyes

32 (Fig. 4) of the members 41 and are equipped with wing nuts 42, washers 43 and jam nuts 44.

Strap bolts 45 provided with nuts 46 connect the brackets with the respective standards.

When the parts are adjusted according to the width between the standards, and the brackets have been placed on the standards, 60 the nuts 46 will be tightened to securely connect the brackets with the standards; and the nuts 42 and 44 will be so adjusted relative to the bolt ends 13 and the members 41 that the vizor 10 will be safely supported on the brackets so that it will not 65 gravitate downward by its own weight, but may be rotated by hand to admit of setting the vizor at various inclinations, according to circumstances.

Having fully described my invention, what I claim as new and desire to secure by Letters Patent is:

A sun shade usable in conjunction with wind shield standards and a wind shield 75 supported thereon, comprising a fabric-covered vizor frame having at each end a laterally extended bolt-end in line with the upper edge of the vizor frame; right and left brackets each having ears, lateral extensions, holes to receive bolts for connecting the brackets with the respective wind-shield standards, and an outwardly, upwardly and forwardly inclined and upwardly extended member having an eye to 80 receive one bolt-end of the vizor frame; strap bolts extending through the eyes of the respective brackets and securing said brackets on the wind-shield standards; and nuts on the respective bolt-ends engaging 85 the respective brackets to secure the vizor at variable inclinations relative to the wind shield supported on the wind shield standards.

In witness whereof I have hereunto signed 90 my name at Springfield, Illinois, this 15th day of December, A. D. 1920.

JOHN P. HUMPHREY.
